JOSEPH MARSHALL, OF NEW YORK, N. Y.

Letters Patent No. 95,244, dated September 28, 1869.

IMPROVED CLOTH AND HAT-BRUSH.

The Schedule referred to in these Letters Patent and making part of the same.

To all whom it may concern:

Be it known that I, JOSEPH MARSHALL, of the city, county, and State of New York, have invented a new and improved Cloth and Hat-Brush; and I do hereby declare that the following is a full, clear, and exact description thereof, which will enable those skilled in the art to make and use the same, reference being had to the accompanying drawing, forming part of this specification, in which—

Figure 1 represents an inverted plan view of my improved cloth and hat-brush.

Figure 2 is a longitudinal section of the same.

Similar letters of reference indicate corresponding parts.

This invention relates to a new brush, which, when used on broadcloth, silk, felt, and other fabric, will very thoroughly free the same of all dust and other impurities, and impart a polish to the surface to which it is applied.

The invention consists in arranging a velvet, plush, or other cushion within the bristles which form the outer part of the brush.

This cushion will aid in removing impurities, and will, at the same time, polish and lay the fibres of the brushed surface.

A, in the drawing, represents the back of the brush, made of wood or other suitable material, of suitable shape.

On it are arranged the bristles *a a*, in the ordinary

manner, but so as to leave an inner space in which a block, B, is placed.

This block may be made in two pieces, so that between them a plush or other velvet covering, *b*, may be clamped, as indicated in fig. 2. It may, however, be of different construction, and springs or other elastic material may be interposed between it and the coverings, so that it will form an elastic cushion of greater or less softness.

This block or cushion is, by means of screws, *c*, or otherwise, fastened to the back of the brush, and fills the space left between the bristles, so that it is entirely or partly surrounded by the same. It may be made adjustable by means of the screws *c*, so that it can have its surface brought in line with, or projecting beyond the ends of the bristles.

The brush is used like every ordinary brush.

Having thus described my invention,

I claim as new, and desire to secure by Letters Patent—

A cloth or hat-brush, containing a cushion, B, which is entirely or partly surrounded by bristles, substantially as and for the purpose herein shown and described.

The above specification of my invention signed by me, this 16th day of July, 1869.

Witnesses: JOSEPH MARSHALL.
